G. CLAUSING.

LAST.

APPLICATION FILED FEB. 28, 1918.

1,295,273.

Patented Feb. 25, 1919.

UNITED STATES PATENT OFFICE.

GEORGE CLAUSING, OF PORTSMOUTH, OHIO, ASSIGNOR TO THE VULCAN LAST COMPANY,
OF PORTSMOUTH, OHIO, A CORPORATION OF OHIO.

LAST.

1,295,273.

Specification of Letters Patent. Patented Feb. 25, 1919.

Application filed February 28, 1918. Serial No. 219,605.

To all whom it may concern:

Be it known that I, GEORGE CLAUSING, a citizen of the United States, and a resident of the city of Portsmouth, in the county of Scioto and State of Ohio, have invented certain new and useful Improvements in Lasts, of which the following is a specification.

One of the objects of the invention is to produce a simple, strong and practical last which can be broken or flexed to the desired extent so as to facilitate the easy and ready removal of the last from the shoe without marring, breaking or pulling the shoe out of shape. In many lasts a V-cut is provided to permit the necessary flexing or moving of the toe and heel parts of the last relative to each other and according to the present invention a construction is provided which permits this V to be made relatively large or long at the top whereby the heel and toe parts can be moved relative to each other a comparatively large amount so as to permit an easy and ready removal of the last from the shoe when desired.

In my Patent No. 1,085,668 dated February 3, 1914, there is shown a last having a toe part and a heel part provided with main bearing members or pins between said parts, and a link pivotally connected at one end to the toe part and at the other end to the heel part for maintaining the last parts in extended or unbroken position relative to each other when the last is being used. In said patented construction there is also employed a spring normally tending to force the heel and toe parts to the unbroken or extended position and also normally tending to maintain said parts in said position. According to the construction of said patent at least one end of the link is provided with a slot in order to permit the toe and heel parts to assume the broken or shortened position when they are moved to said position against the force of the spring.

The present invention contemplates the employment of a last construction such as just referred to but the slotted end of the link has been provided with a depending projection arranged to engage an abutment or stop that is on the last part to which the slotted end of the link is connected and the construction is such that the depending portion of the link is caused to engage said abutment or stop in a manner to draw the toe

and heel parts of the last toward each other 65 against the main bearing pins or members as the toe and heel parts approach the broken or shortened position. In the actual construction of the last I prefer to use as the abutment just referred to one end of the 60 spring and a pivot pin which serves to connect said end of the spring to the part of the last to which the slotted end of the link is connected.

With the construction such as just referred to, that is, a last having a connecting link slotted at one end and provided with a projection which engages a stop upon the last part to which the slotted end of the link is connected, the V portion of the last can be 70 made comparatively large, and the link having the depending portion that engages the abutment, serves to maintain the last parts firmly together even when the last parts occupy the shortened or broken position relative to each other. 75

As showing a specific embodiment of the invention reference is made to the accompanying drawing forming a part of this specification and in said drawing— 80

Figure 1 is a side elevation of a last with the parts thereof shown in extended or unbroken position.

Fig. 2 is a view partially in section showing the parts of the last in shortened or full 85 broken position.

Fig. 3 is a horizontal sectional view taken as on the plane indicated by the line 3—3 of Fig. 1 looking in the direction of the arrows. 90

The last is designated by the reference character A and comprises the forward or toe part B and the rear or heel part C. In the formation of the last these two parts are made integral with each other from the 95 same piece of wood and they are subsequently separated by sawing along the lines Z—Y, Z'—Y, Y—Y' and X—X'. From an inspection of Fig. 1 it will be apparent that the V-portion Z—Y—Z' has been removed from between the upper portions of the toe and heel parts so that said toe and heel parts can assume the shortened or broken position shown in Fig. 2. A hole is also bored at Y for the reception of the 105 main pivot bearing pins D—D' which are maintained in position against outward movement by means of the shoulders d's.

The forward or toe part B of the last is provided with a vertically but longitudinally extending cut b' and the rear or heel part C is provided with a corresponding cut 5 c'. In these cuts there is located the connecting link E which is secured in place by the small pivot pins or rivets e—e'. The link E is preferably a flat metallic strip and has a slot e² at one end thereof. In the construction shown this is at the forward end 10 of the link, although it will be understood the slot could have been located at the rear end of the link if it had been desired to reverse the construction. The pin or rivet e 15 connects the forward or slotted end of the link to the toe part of the last and the pin e' connects the rear end of the link to the heel part of the last. And it will be noted that the slot e² constitutes an opening which 20 is larger than the pin e passing through it. The slotted end of the link is also provided with a depending portion or projection e³ that engages an abutment or stop S when the last parts occupy the broken position 25 shown in Fig. 2 as will hereinafter more fully appear.

The toe and heel parts B and C are also respectively bored at F—F' to provide a receiving space for a spring G which is a 30 tension spring. One end of this spring is secured in place to the toe part of the last by the rivet or pin g while the other end of the spring is secured in place to the heel part of the last by the pin or rivet g', which 35 pins or rivets pass through eyelets at the ends of the springs. The end g² of the spring and the rivet or pin g together constitute the stop or abutment S against which the depending end or projection e³ of the 40 link engages as has been previously stated. It will be observed from an inspection of Fig. 1 that when the last parts occupy the extended or unbroken position shown in Fig. 1 that a line passing through the center of 45 the small rivets or pins e—e' is located below the center of the main bearing pins D—D' and that when the last parts are in the full line position shown in said figure the link E maintains the toe and heel parts 50 in firm engagement with the main bearing pins. At this time the depending end or projection e³ is not in engagement with the stop or abutment S. As the last parts are moved from the unbroken position toward 55 the full broken position the depending end e³ of the link approaches the stop S and engages the stop before the last parts reach the final unbroken position. During this time the slotted portion of the link is sliding 60 along the small pivot pin or rivet E and also during the final portion of this movement toward broken position the depending end e³ is swinging about or to an extent sliding along the stop or abutment S and is 65 causing the toe and heel parts of the last

to hug the main bearing pins or be maintained in proper position relative to each other and relative to the main bearing pins.

When the last parts occupy the position shown in Fig. 2 it will be observed that a line passing through the center of the rivet or pins e—e' is above the center of the axis of the main bearing pins D—D', and in this respect the construction is the same as that shown in my patent previously referred to. 75

In a broad aspect of the invention the depending end or projection e³ constitutes a member that either engages or that is arranged so that it can engage a stop to prevent a disengagement of the last parts from 80 the main bearing pins or members D—D'. It will therefore be seen that the link E constitutes a means for maintaining the last parts in position when they occupy the extended or unbroken position and that the link E also constitutes a means, due 85 to the depending member e³ which can coöperate with the stop S, to maintain the last parts in proper position relative to each other when the last parts occupy the broken 90 position shown in Fig. 2.

While the depending end e³ and the abutment S have been shown as being provided in the toe part of the last it will be manifest that a reversal of the parts could be 95 made and the same result realized by having the projecting portion e³ and its stop or abutment in the heel part of the last instead of in the toe part of the last as is shown in the drawings. 100

The connecting link may broadly be considered as a plate that is secured to one of the last parts and that is pivotally connected by a pin, passing through a slot in the plate, to the other of the last parts. This plate 105 serves to connect and hold the last parts in assembled position when the last parts are in extended or unbroken position relative to each other. An inspection of the drawings and what has preceded will also 110 make it clear that the end of the plate having the slot thereon has a depending hook or projecting member that is arranged to engage a fixed stop or abutment that is located on the last part to which the plate member is pivotally connected by the pin which passes through said slot. Due to this depending projection or hook and the stop or abutment, the last parts can be maintained or held in proper position relative to 115 each other through the medium of the plate when the last parts are in the shortened or full broken position relative to each other. In other words, the depending projection or hook on the plate is arranged to engage the stop and hold the last parts against movement from each other. 120

The improvements herein set forth are not limited to the precise construction and arrangement shown and described and may be 125 130

embodied in various forms and modifications without departing from the spirit and scope of the invention.

What I claim is:

5. 1. A last having a toe part and a heel part provided with horizontally but transversely extending main bearing members, the last also having a link, one end of said link being connected by a pin or rivet to the toe part of the last, and the other end of the link being connected by a pin or rivet to the heel part of the last, one end of said link having a slot through which one of said pins or rivets pass, said slotted end of the link having a projection arranged to co-operate with a stop that is on the last part to which the slotted end of the link is connected so that through the medium of the stop and the link the last parts will be maintained in proper assembled position relative to each other when they are in the shortened or broken position, the link construction also being such that it will hold the last parts in proper assembled position relative to each other when they are in the extended or unbroken position.
2. A last having heel and toe parts between which there are main bearing pins or members, the last being provided with a link having one end secured to the toe part and the other end secured to the heel part, the heel and toe parts also having between them spring means which tend to maintain the last parts in an extended or unbroken position, the spring means being constructed so as to provide an abutment or stop and the link having a projection arranged to co-operate with said abutment or stop so as to provide a means for holding the last parts from moving away from each other when they are in the shortened or full broken position.
3. A last having a vertically but transversely extending saw cut that divides the last into the heel and toe parts, there being provided at the upper portion of the last a V-shaped opening whereby the heel portion of the last can move relatively to the toe portion of the last in order to break or shorten the last, the heel part of the last being provided at the bottom of the V-shaped opening with a pair of main bearing members, the heel and toe parts being connected by a link which is secured at one end by a rivet to the toe part and at the other end by a rivet to the heel part, one of the openings in the link for the reception of the rivet being elongated or greater than the rivet passing therethrough whereby the last parts may assume a full broken position, the slotted end of the link having a depending projection and the last part to which said slotted end of the link is connected having an abutment or stop arranged to be engaged by said depending projection.
4. A last having a heel part and a toe part between which there is provided at the upper portion of the last a V-shaped opening whereby the heel part of the last can move relatively to the toe part in order to break or shorten the last, there being provided a link for connecting said heel and toe parts and also main bearing members or pins which are between said heel and toe parts, one end of said link being connected by a pin or rivet to the toe part and the other end by a pin or rivet to the heel part, one of the openings in the link for the reception of one of the pins or rivets being elongated or greater than the rivet passing therethrough whereby the last parts may assume a full broken position, there also being provided below said connecting link a tension spring which is secured at one end to the toe part of the last at the other end to the heel part of the last, one end connection of said spring serving as an abutment or stop, the slotted end of the link having a projection arranged to co-operate with said abutment or stop and arranged to move toward the abutment or stop as the heel and toe parts are caused to assume a shortened or broken position relative to each other.
5. A last having co-operating heel and toe parts provided between them with main pivot pins against which said parts bear, the last being provided with a link having one end pivotally connected by means of a rivet or pin to the toe part and the other end pivotally connected by means of a rivet or pin to the heel part, one of the rivet receiving openings in the link being enlarged or greater than the rivet or pin therein whereby the last parts can assume a full broken position, said last also having spring means tending to maintain said parts in extended or unbroken position when in said last mentioned position, the end of the link having the enlarged opening being provided with a projection arranged to engage a fixed stop or abutment when the last parts are in shortened or broken position, the spring means being constructed so that it provides said fixed abutment or stop.
6. A last having heel and toe parts provided between them with longitudinally and transversely extending main bearing pins, the last also being provided with a link for connecting and holding said heel and toe parts together and a spring continuously under tension and connected to said heel and toe parts so that they will continuously be drawn against the main bearing pins, the spring also being arranged so that said heel and toe parts will be maintained in extended or unbroken position when in said position, said link having a depending projection arranged to engage an abutment or stop provided by one end of the spring and the rivet

or pin that connects said end of the spring to its corresponding last part.

7. A last having heel and toe parts provided between them with main bearing pins 5 against which each of the last parts bears, the last being provided with a connecting link having a slotted end pivotally secured to the toe part and the other end pivotally secured to the heel part, which link serves 10 to connect the said parts, said link being positioned so that a line passing through the center of said pivots will move from below the center of the main bearing pins to above the center of said main bearing pin as the 15 parts are moved from unbroken position to full broken position, the slotted end of the link having a depending projection and the last part to which the slotted end is connected having an abutment or stop with 20 which the depending projection co-operates when the last parts are in shortened or full broken position.
8. A last having a toe part and a heel part, one of which parts has an abutment or 25 stop, a link connected to said parts, one end of said link having a slot through which passes a pin or rivet that connects the slotted end of the link to the last part having said abutment, said link having a projection 30 arranged to co-operate with the stop or abutment so as to hold said last parts from displacements relative to each other when in shortened or broken position.
9. A last having a toe part and a heel part 35 provided with main bearing members about which one of said parts swings relatively to

the other part, a connecting plate secured to one of said parts and having a slotted connection with the other of said parts and serving to hold said last parts in assembled position when they are in extended or unbroken position, the slotted end of the plate having a depending projection and the last part to which it is connected having an abutment or stop with which said projection co-operates whereby through the medium of said stop and said plate said last parts will be held in assembled position relative to each other when in shortened or full broken position.

10. A last having a toe part and a heel part that swing relatively to each other, a connecting plate secured to one of said parts and having a slotted connection with the other of said parts and serving to hold said last parts in assembled position when they are in extended or unbroken position, the slotted end of the plate having a depending projection and the last part to which it is connected having an abutment or stop with 50 which said projection co-operates whereby through the medium of said stop and said plate said last parts will be held in assembled position relative to each other when in shortened or full broken position.

This specification signed and witnessed this 25th day of February, A. D. 1918.

GEORGE CLAUSING.
